HOLDER FOR A PAIR OF SPECTACLES

Ellen C. Byers, 1933 Keyes Ave., Madison, Wis.

Filed Apr. 13, 1961, Ser. No. 64,725

Term of patent 14 years

(Cl. D57—1)

FIG. 1

FIG. 3

FIG. 2

The broken line showing of the spectacles in FIGURE 1 of the drawings is for illustrative purposes only.

I claim:

The ornamental design for a holder for a pair of spectacles, as shown and described.
